UNITED STATES PATENT OFFICE.

HENRY W. DUBBS, OF ST. LOUIS, MISSOURI.

COMBINED DOOR-BELL AND ALARM.

No. 928,369.

Specification of Letters Patent.

Patented July 20, 1909.

Application filed August 13, 1908. Serial No. 448,360.

To all whom it may concern:

Be it known that I, HENRY W. DUBBS, citizen of the United States, residing at St. Louis, and State of Missouri, have invented 5 certain new and useful Improvements in Combined Door-Bells and Alarms, of which the following is a specification.

The object of my invention is to provide a simple, compact and efficient device where- 10 by the bell which serves as a door bell is also designed to act as a burglar alarm without removing the device from its fixed position on the door. This I accomplish by means of a novel arrangement and construction of 15 the several parts in connection with rollers located on the door and brought in contact with the bell as hereinafter explained. The device is also capable of being used as a window alarm without change in its general 20 construction, the method of operation making it applicable for use as an alarm in any position wherein a movable part will be thrown in contact with a drive wheel ar- 25 ranged to operate the bell-striking mechan- ism.

For a full understanding of the invention and the merits thereof, reference is to be had to the following description and accompanying drawings, in which:—

30 Figure 1 is a plan view of my improved device with the bell case removed and the gong in section, to show the bell operating mechanism. Fig. 2 is a transverse sectional view. Fig. 3 is horizontal sectional view 35 thereof.

Corresponding and like parts are referred to in the following description and indicated in all the views of the drawings by the same reference characters.

40 Referring to the drawings, the numeral 1 designates a portion of a door to which the base plate 2 is fastened in any suitable manner, as by screws through the opening 2, as shown. The lever 3, fulcrumed on said base 45 plate 2 and held in position by a screw 4, serves to throw the device into and out of its operative and passive positions. Attached to the end of the lever 3 by means of a slot formed therein is a spring 5, the other end of 50 which is secured in a similar slot in the lug 6 on the bell case 7, said lug forming a part of the bell case, and tension exerted on the spring 5 by movement of the lever 3 in either direction holds the device from lateral move- 55 ment when occupying an operative position.

The numeral 8 designates a drive wheel

mounted in the lower portion of the bell case 7 and extending below the same, adapted to engage the face of a roller 9 mounted on the end of the spindle 10 located on the inner 60 side of the door, said roller being made adjustable by means of a set screw. Attached to the other end of the spindle 10 and located on the outside of the door is a crank handle 12 by means of which the roller 9 is 65 actuated to turn the drive wheel 8 when in use as a door bell. On the opposite side of the drive wheel 8 and occupying the same relative position to the drive wheel 8 as the roller 9, is a rubber roller 13 attached to the 70 end of the spindle 14 extending through the door from the door knob, and by means of which the roller 13 will be actuated to turn the drive wheel and set the bell mechanism in motion when in use as an alarm. 75

Mounted in the bell case by means of a screw bolt 15 immediately above the drive wheel and engaging the face thereof is a roller 16, said roller carrying at its outer end a ratchet wheel 17. 80

18 designates a striker frame pivotally mounted in the bell case 7 by means of a screw bolt 18' and provided with teeth 19 and oppositely extending arms 20, each carrying a striker 21. The teeth 19 alternately 85 engage the teeth of the ratchet wheel 17, thereby imparting a rocking or to and fro motion to the frame 18 and causing the strikers 21 on the arm 20 to come suddenly in contact with the lugs 22 on the inner face of 90 the bell or gong 23. Additional stress upon the striker arm 20 in order to alternately disengage the teeth 19 from the ratchet wheel 17 is secured by means of a spring 20', the opposite ends of which are secured to the striker 95 frame 18 and bell case 7. A screw 24 passing through the case 7 and gong 23 holds the gong rigidly in place so that the strikers 21 will invariably come in contact with the lugs 22 on the inner face. 100

In order to insure a good contact surface, the roller 9 is provided with a rubber band 25 around its periphery and similar bands 26 and 27 are employed on the peripheries of the drive wheel 8 and ratchet roller 16 105 respectively. The lever 3 is provided on its outer face with a knob 28 for manipulation in either direction, the extent of such movement being governed by lugs 29 on the base plate 2. A guide 30 on said base plate 2 110 working in a recess or slot 31 formed in the lever 3 is also employed to control the move-

ment. The numeral 32 designates a screw bolt passing through both sides of the lower portion of the bell case 7 and while serving as a bearing for the drive wheel 8 acts as a support for the lower portion of the bell case. The screw bolt 4 passing through openings in the base plate 2 and lever 3 and the bell case 7 movably secures the several parts in their proper position relative to 10 each other.

With this arrangement shown, the operation of the device is as follows:—The device when in use as a door bell occupies a position sufficiently close to the roller 9 to allow the drive wheel to engage said roller and receive the motion imparted therefrom. In this position the crank handle 12 when turned in either direction by means of the roller 9 will rotate the drive wheel 8 which 20 in turn rotates the ratchet roller 16 and ratchet wheel 17, said ratchet wheel alternately engaging the teeth 19 and the striker frame 18 and imparting to said frame a to and fro motion and causing the strikers 21 25 on the striker arms 20 to come suddenly in contact with the lugs 22 on the inner face of the gong. As a burglar alarm the operation is the same when the drive wheel 8 is moved in contact with the roller 13 motion 30 being primarily imparted in that event by the turning of the door knob and roller 13.

Without change in its general construction, the device is applicable as a burglar alarm in any position wherein a movable 35 part will engage and rotate the drive wheel 8 thereby setting the bell-operating mechanism in motion to sound an alarm.

Having thus described the invention, what is claimed as new is:—

40 1. In a device of the character described, a base plate, a bell case movably mounted thereon, a drive wheel mounted within and projecting out of the bell case, a roller mounted within the bell case and located in 45 close proximity with said drive wheel to receive imparted motion therefrom, a ratchet wheel rigidly attached to the face of said roller, a pivoted striker frame mounted within said bell case and coöperating with 50 said ratchet wheel, and a striker carried by said frame, substantially as described.

2. In a device of the character described, a base plate, a bell case movably mounted thereon, a bell gong mounted within said 55 bell case and provided with lugs on its inner face, a drive wheel mounted within and pro-

jecting out of the bell case, a roller mounted within the bell case in close proximity with said drive wheel to receive imparted motion therefrom, a ratchet wheel rigidly attached to the face of said roller, a pivoted two arm striker frame mounted within said bell case and coöperating with said ratchet wheel and a striker carried by each arm for contact with lugs on the inner face of the gong substantially as described. 60

3. In a device of the character described, a base plate, a bell case movably mounted thereon, a lever fulcrumed to said base plate and having a spring connected with said bell case, a drive wheel mounted in and projecting out of the bell case and oppositely disposed contact rollers for imparting motion to the drive wheel when thrown in contact therewith by means of said lever substantially as described. 70

4. In a device of the character described, a base plate, a lever fulcrumed on said base plate, a bell case movably mounted upon said base plate, a spring connecting the lever and bell case, and a drive wheel mounted within and projecting out of the bell case adapted to be thrown by said lever into contact with a moving surface to receive motion imparted therefrom substantially as described. 80

5. A device of the character described comprising a base plate, a bell case pivotally mounted thereon, a gong carried by said case, a striker mounted within the case and arranged to tap the gong, and a drive wheel 90 journaled in the case and having an operative connection with said striker and adapted to be rotated while occupying a position in the plane of the swinging movement of said bell case. 95

6. A device of the character described, comprising a base plate, a lever fulcrumed thereon, a bell case pivotally mounted on the base plate, a spring connecting said case to one of said levers, means for holding the lever on the base plate in different positions, a gong mounted within said case, a striker for said gong, a drive wheel in said case, and a drive connection between said drive wheel and said striker. 100

In testimony whereof I affix my signature in presence of two witnesses.
